CO., OF SAN FRANCISCO, CALIFORNIA, A CORPORATION OF DELAWARE

TURBINE PUMP

Application filed December 23, 1929. Serial No. 415,912.

This invention relates to a turbine or centrifugal pump and while adapted for horizontal and surface turbine pumps, it is particularly suitable for deep well centrifugal pumps in which the pump is suspended in a well hole. 55

It is the general object of the present invention to provide a turbine or centrifugal pump comprising one or more stages in which the bowls of the different stages are constructed in a novel manner, tending to simplify the manufacturing, reduce cost, and facilitate assembling the pump, while securing at the same time superiority in operation. 60

15 A turbine or centrifugal pump of the multi-stage type comprises an impeller shaft bearing a number of pump runners or impellers. These pump runners take suction at their lower center and discharge a revolving stream 20 of water from their peripheries. The peripheries of the impellers discharge the water into a diffusion chamber from which the water or other liquid is passed to a return chamber, the function of which is to return the water 25 or other liquid to the center of the succeeding higher impeller and at the same time by means of vanes, to remove the vortex motion of the water. The diffusion chamber may or may not contain vanes, but if the diffusion 30 chamber contains vanes, they are at a different angle than the vanes of the return chamber. As ordinarily constructed, the diffusion and return chamber of each stage of the pump is built in a single unit and these units are 35 provided with means by which the several stages of the pump may be connected together. As thus constructed, the impellers of each stage of the pump must be placed in position on the impeller shaft as each bowl 40 is positioned, involving an expensive assembly operation which has the disadvantage that it is difficult to properly align the impellers in the bowls. 65

I have found that by constructing the 45 diffusion chambers and return chambers of the bowls in separate units and providing them with self-aligning faces or flanges and by additionally providing a separate means, independent of the body of the bowls, for 50 clamping all of the bowls and their parts together, a pump is provided in which the parts may be more economically produced, the desired shapes of the chambers more accurately attained and moreover, a pump is provided in which the bowls of the pump may be placed in position after all of the impellers and runners of the pump have been accurately placed upon the impeller shaft. Moreover, the whole rotating element with all its assembled impellers may be taken and dynamically balanced. This can not normally be done since the normal bowls are not constructed so that they may be applied to the shaft after the impellers have been assembled. 70

In a turbine pump of this class the impellers eject a revolving stream of fluid in which about a half of the energy in the fluid is in the form of velocity and about a half pressure. I have found that by constructing the diffusion chamber and the return chamber in separate parts that the vanes of the diffusion chamber may be best shaped for converting the velocity component of the fluid into pressure while directing the fluid upward in the pump rather than radially. By providing diffusion vanes forming passages of expanding cross sections and angled upwardly, the velocity component of the fluid may to a large extent, be converted into pressure. Then for providing a larger chamber before the fluid hits the vanes of the return chamber, the best recovery of energy of the fluid is effected. 75

Moreover, by separating the diffusion 80 chamber and the vanes for removing the residual vortex of the fluid from each other by non-vane chambers and by building the diffusion chamber and return chamber of separate parts, the cleaning of the mold 85 chambers may be most readily effected.

The present invention, together with various additional objects, advantages and features thereof will best be understood from a description of the preferred form or example 90 of a pump embodying the invention. For this purpose there is hereafter described, with reference to the accompanying drawing, one example of a turbine or centrifugal pump 95 embodying the present invention. 100

In the drawing:

Figure 1 is an elevation mainly in vertical section of the pump.

Figure 2 is a section through the diffusion chamber on the line 2-2.

Figure 3 is a section through the return chamber on the line 3-3 of Figure 1.

Referring to the drawing, 1 indicates the impeller shaft which in practice may be connected with additional shaft sections and led to the surface of the well where it may be driven by any suitable means. The impeller shaft 1 has rigidly connected therewith a plurality of impellers or pump runners 2, 15 three of which are indicated. These impellers 2 are secured rigid with the shaft 1 by suitable means, such as the set screws 3. The impellers 2 are provided with fluid passages including the inlet-ends 4 which are at the 20 center and lower ends of the impellers which lead the fluid pump to the peripheral discharge-ways 5 of the impellers. Any preferred or desired form of impeller may be employed.

Each impeller is housed in a pump bowl 6 and said pump bowls 6 are divided into a lower part 7 and an upper part 8, the lower part 7 providing a diffusion chamber which receives the fluid from the periphery of the 30 impeller of the stage and passes the fluid upwardly past the impeller to the return chamber 8. The diffusion chamber 7 is provided with upwardly slanting vanes 9 which lead the fluid, leaving the impeller 2 radially, in 35 an axial direction upwardly through the pump.

The vanes 9 of the diffusion chamber are brought closer together at their lower ends and their upper ends form expanding passages slanting upwardly which permit the 40 velocity component of the fluid to be changed into pressure. The return chambers 8 form an open chamber 10a adjacent the chamber of the diffusion member and the latter half 45 of the return chambers are provided with vanes 10 lying substantially in vertical planes, the function of which is to remove the residual vortex action of the fluid. The passages of the return chamber 8 lead back 50 to the center of the pump feeding the fluid in an upwardly passing smooth stream to the inlet end of the impeller passages to the succeeding higher impeller of the pump.

By constructing the diffusion chambers 7 55 separate from the return chamber 8 of the bowl, it is possible to cast these parts more readily, particularly in the smaller sizes and in addition thereto, vanes 9 and 10 of these chambers may be more accurately formed 60 so that they are better adapted for their separate action.

Preferably, the upper parts or members of the pump bowls are diametrically divided 65 into equal parts *a* and *b* in order that the pump may be more readily assembled and

the separate halves of the upper parts of the bowls or diffusion chambers are provided with flanges 12 receiving bolts 13 or otherwise formed with means for retaining the halves united. In certain cases, however, I 70 rely solely upon the additional means provided in the pump for clamping the pump bowls together in connection with the hereinafter described interfitting flanges of the upper and lower bowl parts for retaining 75 the halves of the return chamber united.

The minimum inner diameter of the diffusion chambers 7 is made slightly larger than that of the outer diameter of the runners or impellers 2 so that the diffusion chambers 80 may be slipped axially over the impellers 2 when they are assembled upon the impeller shaft 1. The diffusion chamber 7 and return chamber 8 are formed with suitable interlocking faces designed for axially aligning these chambers in the desired position and for clamping the halves of the return chambers together.

These interlocking faces are preferably 85 formed by centering flange 14 on the bottom of the return chamber adapted to have an arcuate machine fit with the inner bore of the diffusion chambers 7. There is also provided an annular recess 15 at the upper end of the return chambers adapted to receive 90 the lower end of the diffusion chamber 7 of the succeeding higher stage. The diffusion chamber below the return chamber thus has a centering interlocking fit with the return chamber and the diffusion chamber above the return chamber has a similar fit, with the result that the different parts of the pump bowls are axially aligned and the halves 95 of the return chambers held together in operation.

The pump bowls and their constituent parts are preferably axially held together by a single clamping member which is illustrated as preferably composing a sleeve 16 forming also a housing for the bowls of 100 the impellers.

The sleeve 16 is indicated as threaded at its lower end 17 to the usual suction case 18 of the pump which is provided with a ring 19—a engaging the lower end of the lowest 115 diffusion chamber of the pump. The upper end of the sleeve 16 is threaded, as indicated at 19, to a pump neck or top case member 20 which encloses the upper impeller of the pump and leads the fluid to the usual discharge casing (not shown) of the pump which is connected to the threads 21. The neck or top casing of the pump provides a packing chamber 22 and suitable means 23 for connection with the inner casing of the line shafting of the pump which houses the impeller shaft 1. The top casing 20 engages the groove of the upper pump runner. By turning the top casing relative to the lower casing or suction case, the retaining 120

sleeve 16 tightens these two casings against the collection of pump bowls and parts, firmly pressing the same together in an axial direction and locking them in the desired operating positions.

The suction case 18 is shown as provided with webs 30 leading to a bearing 31 for the lower end of the impeller shaft 1. The lower end of the suction case 18 is internally threaded, as indicated at 32, so that it may be attached to the screen in the usual manner.

With the turbine pump thus described, the impellers 2 may all be accurately positioned on the impeller shaft 1 before the remainder 15 of the pump is assembled. The diffusion chambers 7 may then be passed over the lower end of the impeller shaft and over the impellers to their desired positions. The separate halves of the return chambers can be 20 placed in position and engage with the bearing faces of the diffusion chambers and thus held from parting. By connecting then the top and bottom casing with the retaining sleeve 16, the entire assembly is immediately 25 brought together with all parts accurately in the desired operating position.

While the particular form of turbine pump herein described is well adapted for carrying out the objects of the present invention, various 30 modifications and changes in detail of the parts may be made without departing from the spirit and objects of the invention and this invention includes all such changes and modifications as come within the scope of the 35 appended claims.

I claim:

1. A turbine pump comprising an impeller shaft, an impeller on said shaft, a pump bowl including a diffusion chamber member having 40 vanes which spiral upward and outward, being radial at their lower ends and axial at their upper ends, a return chamber member having flange interlocking fit with said diffusion chamber member, said return chamber member having substantially vertical vanes, the return chamber member being divided in a 45 vertical plane, and means for axially compressing the pump bowl parts for retaining the interlocking faces thereof together.

2. A turbine well pump comprising a vertical shaft including a plurality of impellers, diffusion chambers for said impellers capable of being axially slipped over the impellers while they are assembled on the impellershaft. 55 return chambers for said impellers divided in vertical planes and adapted to be assembled with the impellers and diffusion chambers in place, interlocking faces on said diffusion chambers and return chambers, and a common retaining member for retaining the diffusion chambers and return chambers from 60 axially separating.

3. A turbine well pump comprising an impeller shaft including a plurality of impellers, pump bowls for said impellers, said

pump bowls comprising a separate diffusion chamber member and a separate return chamber member, the diffusion chamber member having vanes which spiral upward and outward being radial at their lower ends and axial at their upper ends, the return chamber forming open passages adjacent the diffusion member and being provided with vanes lying in axial planes.

4. A turbine well pump comprising an impeller shaft including a plurality of impellers, pump bowls for said impellers, said pump bowls comprising a separate diffusion chamber member and a separate return chamber member, the diffusion chamber member having vanes which spiral upward and outward being radial at their lower ends and axial at their upper ends, the return chamber forming open passages adjacent the diffusion member and being provided with 75 vanes lying in axial planes, and a common means for clamping the plurality of pump bowls together and holding the diffusion chamber members and return chamber members together.

Signed at Los Angeles, California, this 10th day of December, 1929.
